Primary Examiner — Kevin K Rudzinski*Assistant Examiner* — Paul D Bohannon(74) *Attorney, Agent, or Firm* — Banner & Witcoff, Ltd.(57) **CLAIM**

The ornamental design for a chair, as shown and described.

DESCRIPTION

FIG. 1 is a front perspective view of a chair showing my new design;

FIG. 2 is a right side view thereof;

FIG. 3 is a front view thereof;

FIG. 4 is a rear view thereof;

FIG. 5 is a bottom view thereof;

FIG. 6 is a cross-sectional view taken along the line 6-6 in FIG. 2; and,

FIG. 7 is a cross-sectional view taken along the line 7-7 in FIG. 3.

The broken lines shown in the drawings illustrate portions of the chair that form no part of the claimed design.

1 Claim, 5 Drawing Sheets(56)
